CHARLES M. HODGES, OF MANSFIELD, MASSACHUSETTS, ASSIGNOR TO
HIMSELF, WILLIAM O. CAPRON, AND NATHANIEL WHITMORE.

Letters Patent No. 72,638, dated December 24, 1867; antedated June 10, 1867.

IMPROVEMENT IN SCYTHES.

The Schedule referred to in these Letters Patent and making part of the same.

TO ALL PERSONS TO WHOM THESE PRESENTS SHALL COME:

Be it known that I, CHARLES M. HODGES, of Mansfield, in the county of Bristol, and State of Massachusetts, have invented a new and useful Improvement in Scythes; and do hereby declare the same to be fully described in the following specification and represented in the accompanying drawings, of which—

Figure 1 is a side view of a scythe-blade made in accordance with my invention.

Figure 2 is a back edge view of it.

Figure 3 is a transverse section of it.

Figure 4 is a view of the back piece as separate from blade and cap or stiffening-plate.

In the drawings, A denotes a thin plate of steel, of the form required for a blade. B is a stiffening-plate or strip of metal bent transversely with the angular form, as shown in fig. 3, and laid upon the blade A, so as to stand at an acute angle therewith, the arrangement of the blade and its stiffening-plate or cap being as represented in the drawings. The said cap-plate is to be secured to the blade by solder run into the angular space between the two, and so as to pass between the flat-surface portions of the two which are in contact. The solder, however, is to extend into the angular space but a very short distance, if any, from its vertex or the junction of the two plates. The receiving part of the angular space between the two plates is to receive a back piece, C, formed as shown in figs. 3 and 4, such back piece being triangular or trapezoidal in its transverse section. The said back piece projects from the heel part D of the scythe, or is formed of one piece of metal with it, and may be made of what is termed "malleable cast iron." The said back piece is to be fastened to the blade A and the cap, by means of screws s s going into them laterally.

When the blade may become worn out or rendered useless, it may be easily removed from the back piece and another blade be put in its place on such back piece. The cap-plate B, formed and applied to the blade A in manner as described, operates to great advantage to stiffen such blade; and furthermore, by forming a channel for reception of the solder, it can be connected to the blade to much better advantage than it could be were it a flat plate instead of being made or bent in the angular form, as exhibited.

I make no claim to a scythe as made with a grooved back and a blade to enter the groove of such back.

What I claim as my invention, is—

The combination as well as the arrangement of the back piece C with the blade A and the cap-piece B, arranged and applied with respect to each other as set forth.
